UNITED STATES PATENT OFFICE.

MICHAEL G. KUHN, OF NEW YORK, N. Y.

LOCK-HINGE.

SPECIFICATION forming part of Letters Patent No. 349,850, dated September 28, 1886.

Application filed January 21, 1886. Serial No. 189,248. (No model.)

To all whom it may concern:

Be it known that I, MICHAEL G. KUHN, of the city, county, and State of New York, have invented certain new and useful Improvements in Lock-Hinges, of which the following is a specification.

This invention relates to an improved shutter lock-hinge, by which the shutter is reliably locked when in open position.

10 In the accompanying drawings, Figure 1 represents a front elevation of two shutters with my improved lock-hinge, showing the same respectively in position for locking the shutter in open position and in position when the shutter is released. Fig. 2 is a front view of my improved lock-hinge, drawn on a larger scale; and Fig. 3 a side elevation, with a part broken away and shown as applied to a shutter.

15 20 Similar letters of reference indicate corresponding parts.

Referring to the drawings, A represents my improved locking-lever, which is made in the shape of an L-shaped hook, and provided at 25 the angle of the hook with a laterally-bent thumb-piece, a, by which the said lever can be readily taken hold of for placing it in locked or unlocked position. The opposite end of the lever or fastener A is pivoted either to a

30 forwardly-extending ear, b, of the supporting-plate B of the lower hinge-pintle, C, or to the pintle-socket C', as desired. The supporting-plate B is screwed or otherwise attached to the wall in the usual manner. The ear b is either made integral with the supporting-plate B or riveted thereto, as desired. The rear die of the fastener A, back of the pivot-connection with the ear b, is made straight, as shown at D, Fig. 3, and provided 35 40 with enlarged and rounded-off side portions, d. (Shown in Fig. 3.) The free end of a tension-spring, D, that is riveted at one end to the supporting-plate B, presses against the straight rear edges of the fastener A at or against the enlarged side portions or heels, d, of the same, according as the fastener is placed in a position for locking or releasing the shutter. The tension-spring D serves to bind on 45 50 the straight part at the rear end of the fastener A, so as to hold the same in horizontal

position, as shown in Fig. 3, or on the enlarged heel d, for retaining it in downward position, as shown in full lines in Fig. 2, and in dotted lines in Fig. 3. The locking lever or fastener A is made long enough, so that its 55 upwardly-extending part will engage the hinge-strap E, that is attached to the shutter and hinged to the pintle C. When the shutter is opened, the fastener A is thrown in upward position by taking hold of the thumb-piece a, so that its upwardly-extending arm engages the horizontal part of the hinge-strap E, as shown on the left side of Fig. 1, and in Fig. 3. The fastener A is held in this position by the spring D, so that the shutter is locked 60 in open position without being released by the action of the wind on the shutter. When the shutter is to be closed, the fastener is lowered by taking hold of the thumb-piece a, so that the fastener clears the hinge-strap E, the fastener being retained in lowered position by the pressure of the spring D against the enlarged heel d.

The hinge is furnished with the fastening device, which adds but little to the expense of 75 the same, and forms a simple device for locking the shutter in open position, so as to retain it even when the shutter is exposed to heavy storms.

Having thus described my invention, I claim 80 as new and desire to secure by Letters Patent—

The combination, with the pintle member of a lock-hinge provided with a forwardly-extending ear, of a locking lever or fastener pivoted to said ear and adapted to swing in a plane 85 at a right angle to the face of the shutter, and to engage the inner edge of the shutter, said fastener being provided at its pivot end with a straight rear edge and with laterally-extending heels, and with a thumb-piece at its front 90 end, and a tension-spring applied to said pintle member and adapted to bear against said pivot end, substantially as described.

In testimony that I claim the foregoing as my invention I have signed my name in presence of two subscribing witnesses.

MICHAEL G. KUHN.

Witnesses:

PAUL GOEPPEL,
MARTIN PETRY.
